United States Patent Office

Des. 211,945
Patented Aug. 13, 1968

211,945

HUMIDIFIER

Hans Rudolf Stoop, Mutschellen, and Karl Flury, Dietikon, Switzerland, assignors to Defensor AG, Zurich, Switzerland, a Swiss corporation

Filed Nov. 8, 1967, Ser. No. 9,328

Claims priority, application Switzerland May 16, 1967

Term of patent 14 years

(Cl. D23—146)

FIG. 1

FIG. 2

FIG. 4

FIG. 5

FIG. 3

FIGURE 1 is a perspective view of the humidifier embodying our new design;

FIGURE 2 is a front view thereof;

FIGURE 3 is a side view thereof;

FIGURE 4 is a top plan view thereof; and

FIGURE 5 is a bottom plan view thereof.

The undisclosed back and remaining side of the humidifier is identical to the front and side shown in FIGURES 2 and 3 respectively.

The dominant features of our design reside in the portions shown in full lines.

We claim:

The ornamental design for a humidifier, substantially as shown and described.
